CLAIM

The ornamental design for a casement window, as shown in the drawings.

DESCRIPTION

FIG. 1 is an enlarged front elevational view of one window of the casement window;

FIG. 2 is a front elevational view of the casement window in fixed and operable positions; and,

FIG. 3 is an enlarged fragmentary view of one window of the casement window in operable position.

The broken lines are for illustrative purposes only and form no part of the claimed design.
